UNITED STATES PATENT OFFICE.

CHARLES G. CLEMENT, OF EDGERTON, WISCONSIN, ASSIGNOR TO HIGHWAY TRAILER COMPANY, OF EDGERTON, WISCONSIN, A CORPORATION OF WISCONSIN.

TILTING-BODY LOCK.

Application filed August 24, 1925. Serial No. 51,902.

This invention relates to a load-carrying vehicle having a body adapted for tilting laterally for discharging its load and the purpose of the invention is to provide locking means and convenient controls therefor for holding the body firmly in load-carrying position or releasing it promptly for discharging its load. It consists in certain features and elements of construction in combination as herein shown and described and as indicated by the claims.

In the drawings:

Figure 1 is a top plan view of the vehicle frame with the body removed.

Figure 2 is a side elevation partly in section showing the body on the frame in load-carrying position.

Figure 3 is a partial end elevation with certain parts in section showing the locking device.

Figure 4 is a vertical section of the locking bolt and associated parts.

Figure 5 is a detail perspective view of certain parts of the operating drum for the locking bolts.

The invention is shown applied to a trailer vehicle of the type embodying a drop frame, 1, carried on wheels, 2, and provided with cross rails, 3, 3, upon which rest the channeled rockers 4, 4, of the hopper body 5. By virtue of this mounting the body is adapted to roll toward one side or the other for tilting to discharge its load. For locking it against such rolling motion each end of the body is fitted with a socket member, 6, and a locking bolt, 7, is slidably carried in a guide fitting, 8, which forms the upper terminal of an A frame, 9, supported on the terminal portions, 10, of the main frame. Check chains, 11, extend from each side of the body at its upper edge downwardly into connection with springs, 12, which supplement the locking bolts, 7, for holding the body in its central upright position. However, upon release of one of the check chains and the locking bolts, 7, the tension of the spring, 12, at the other side will initiate the rolling action and tend to quicken the discharge of the load. Each of the chains, 11, is connected to the spring, 12, by means of an L-shaped lever, 13, pivotally engaged with an eye, 12^a, at the upper end of the spring and having a tail piece, 13^a, hooked into a link of the chain, 11. The longer arm of the lever, 13, is held approximately parallel with

the chain, 11, by a retaining link, 11^a, but when this link, 11^a, is lifted off the end of the lever the short end, 13^a, is tilted up by the tension in the parts thus releasing the chain, 11, and leaving the body subject only to the stress of the chain at the other side. As shown the lower ends of the springs, 12, are conveniently anchored to a cross member, 14, on the frame at about the middle of its length.

Since to permit the dumping action it is necessary to simultaneously release the locking bolts, 7, at both ends of the body I have found it convenient to provide a rock shaft, 15, not far from the middle of the length of the frame and fitted at both ends with crank arms, 16, and foot pedals, 17. The shaft, 15, carries a winding drum comprising two members, 18, and a central connecting portion, 19, the latter being keyed to the shaft, 15. Cables, 20 and 21, extend from the respective sections, 18, of the drum toward opposite ends of the vehicle, the cable, 20, passing over a guide pulley, 22, a second pulley, 23, and a third pulley, 24, the last two pulleys being carried by the A frame, 9, at one end of the trailer. The extreme end of the cable, 20, terminates in a plug, 25, secured in the upper end of the locking bolt, 7. A coil spring, 26, pocketed in the lower end of the bolt and reacting against the flange, 27, of the fitting, 8, holds the bolt normally at its upper limit in engagement with the socket, 6, but as the foot pedal, 17, is depressed rotating the shaft, 15, and drum, 18, the bolt, 7, is withdrawn downwardly by the cable, 20, and thus disengaged from the socket, 6.

Simultaneously a similar movement is transmitted through the cable, 21, passing over pulleys, 28, 29 and 30, and connected with the bolt, 7, at the other end of the vehicle. The foot pedal, 17, being arranged quite near to the check chain, 11, it is possible for the operator to uncouple the chain, 11, from the spring, 12, by hand and release the locking bolts, 7, by the pressure of his foot upon the pedal, 17, at the same time, thus allowing the tension of the spring, 12, at the opposite side of the vehicle to draw the body over for discharging its contents at the far side. When empty a hopper body of this design is substantially balanced so that it can be readily rolled back to central position by hand and as it arrives at this position the locking bolts, 7, will snap into the sockets, 6,

by virtue of the inclined approaches, 6^a, on the latter.

The peculiar construction of the winding drum as indicated in Figures 1 and 5, permits proper equalization in the tension of the cables, 20 and 21, so as to insure that the bolts, 7, will be actuated simultaneously. Each winding section, 18, is formed with a few lateral projecting teeth or lugs, 18^a, while the middle section 19, which is keyed to the shaft, 15, is formed with a closely spaced series of notches, 19^a, opening towards opposite sides so that the sections, 18, may be rotatively adjusted independently of each other, each to the position at which its cable is just taut; then the lugs, 18^a, are entered in whichever notches, 19^a, happen to register with them under this condition and a set screw 18^b, in the section, 18, is tightened on the shaft to hold the parts in this assembled relation.

I claim:

1. In a vehicle comprising a frame and a body mounted to tip laterally in either direction at will to discharge its load, a yielding check strap at each side of the body coupled to the frame, a positive lock at each end of the body for steadyng it on the frame, a disengageable connection in each of said check straps, and releasing means coupled to each lock operable simultaneously and having operating members adjacent both of said check straps.

2. In the combination defined in claim 1, said releasing means comprising a rock shaft extending across the vehicle adjacent the check straps with a crank arm at each end of said rock shaft.

3. In a vehicle comprising a frame and a body mounted to tip laterally thereon for discharging its load, a yielding check chain at each side of the body disengageably connected with the frame, a locking bolt at each end of the frame engaging the body to steady it in upright position, a pull cable extending

from each bolt for releasing it, a rock shaft 45 extending across the vehicle under the body adjacent the check chains, an operating crank at each end of said shaft and a drum on the shaft on which the pull cables are wound for simultaneously releasing the bolts when the 50 rock shaft is turned.

4. In a vehicle comprising a frame and a tilttable body thereon, a pair of locking devices arranged to engage the body at its opposite ends respectively, and means for releasing said locks simultaneously including a winding drum, pull cables wound thereon and extending to said locking devices respectively and means for turning the drum, said drum comprising three parts, one of which 60 is operatively secured to the turning means, each of the other parts having one of the cables connected with it and being rotatively adjustable with respect to the first part and engageable therewith at short intervals of 65 adjustment to provide the means for tightening the cables independently of each other.

5. In a vehicle comprising a frame and a tilttable body thereon, a pair of locking devices arranged to engage the body at its opposite ends respectively, and means for releasing said locks simultaneously including a winding drum, pull cables wound thereon and extending to said locking devices respectively and means for turning the drum, said 70 drum comprising three parts, one of which is operatively secured to the turning means and is formed with a plurality of notches open toward the other two parts, each of the other parts having one of the cables connected with 75 it and having one or more lugs to engage said notches, said other parts being rotatively adjustable with respect to the first part for selective engagement of the lugs and notches to provide the means for tensioning the cables 80 individually.

CHARLES G. CLEMENT.
